(57) **CLAIM**

The ornamental design for a display screen or portion thereof with graphical user interface, as shown and described.

DESCRIPTION

FIG. 1 is a front view of a display screen or portion thereof with graphical user interface showing our new design according to a first embodiment;

FIG. 2 is a front view of a display screen or portion thereof with graphical user interface showing our new design according to a second embodiment;

FIG. 3 is a front view of a display screen or portion thereof with graphical user interface showing our new design according to a third embodiment;

FIG. 4 is a front view of a display screen or portion thereof with graphical user interface showing our new design according to a fourth embodiment;

FIG. 5 is a front view of a display screen or portion thereof with graphical user interface showing our new design according to a fifth embodiment;

FIG. 6 is a front view of a display screen or portion thereof with graphical user interface showing our new design according to a sixth embodiment;

FIG. 7 is a front view of a display screen or portion thereof with graphical user interface showing our new design according to a seventh embodiment;

FIG. 8 is a front view of a display screen or portion thereof with graphical user interface showing our new design according to an eighth embodiment;

FIG. 9 is a front view of a display screen or portion thereof with graphical user interface showing our new design according to a ninth embodiment;

FIG. 10 is a front view of a display screen or portion thereof with graphical user interface showing our new design according to a tenth embodiment;

(Continued)

FIG. 11 is a front view of a display screen or portion thereof with graphical user interface showing our new design according to an eleventh embodiment;

FIG. 12 is a front view of a display screen or portion thereof with graphical user interface showing our new design according to a twelfth embodiment;

FIG. 13 is a front view of a display screen or portion thereof with graphical user interface showing our new design according to a thirteenth embodiment;

FIG. 14 is a front view of a display screen or portion thereof with graphical user interface showing our new design according to a fourteenth embodiment;

FIG. 15 is a front view of a display screen or portion thereof with graphical user interface showing our new design according to a fifteenth embodiment; and,

FIG. 16 is a front view of a display screen or portion thereof with graphical user interface showing our new design according to a sixteenth embodiment.

The outermost broken lines in the figures depict a display screen or portion thereof and form no part of the claimed design.

The remaining broken lines in the figures depict portions of the graphical user interface which form no part of the claimed design.

The grayscale tones shown in the figures represent a contrast in appearance.
